HENDRIK STUKART, OF ROTTERDAM, NETHERLANDS, ASSIGNEE TO U. S. SLICING
MACHINE COMPANY, OF CHICAGO, ILLINOIS, A CORPORATION OF ILLINOIS.

SLICING-MACHINE.

1,144,507.

Specification of Letters Patent. Patented June 29, 1915.

Application filed March 31, 1913. Serial No. 757,863.

To all whom it may concern:

Be it known that I, HENDRIK STUKART, a subject of the ruler of the Netherlands, residing in Rotterdam, Netherlands, have invented certain new and useful Improvements in Slicing-Machines, of which the following is a specification.

This invention relates to improvements in slicing machines and one of the objects of 10 the invention is to provide an improved machine of this class having simple, durable and efficient means whereby any slack or lost motion may be readily and quickly taken up in the cutter operating mechanism without dismantling the parts.

A further object is to provide an improved machine of this class having means for prolonging the usefulness of the cutter as the latter wears away.

20 To the attainment of these ends and the accomplishment of other new and useful objects as will appear, the invention consists in the features of novelty in substantially the construction, combination and arrangement of the several parts hereinafter more fully described and claimed, and shown in the accompanying drawings exemplifying the invention and in which—

Figure 1 is a front elevation of a machine 30 having an attachment applied thereto constructed in accordance with the principles of this invention. Fig. 2 is a sectional view on line 2—2, Fig. 1. Fig. 3 is a sectional view on line 3—3, Fig. 2. Fig. 4 is a detail sectional view on line 4—4, Fig. 2. Fig. 5 is an enlarged detail sectional view taken on line 5—5, Fig. 3. Fig. 6 is a view similar to Fig. 4 of a modification.

Referring more particularly to the drawings and in the present exemplification of this invention the numeral 10 designates generally the reciprocating support upon which the meat or article to be sliced is placed and 11 designates the cutter with respect to which the support 10 is reciprocated. A support 12 in the form of a housing is arranged adjacent the path of reciprocation of the support 10 and extends upwardly above the carriage 10 to form a support for 50 the cutter 11. This cutter 11 is in the form of a disk as shown and has secured thereto a shaft 12^a which is rotatably mounted in a bearing 13. In the form of the invention shown in Figs. 2 and 4 the bearing 13 is eccentrically mounted in a bushing 14 and is

held against rotation with respect to the bushing in any desired or suitable manner such as by means of a fastening device 15. The upper end of the housing 12 which forms the main support for the cutter 11 is 60 preferably split as at 16 and is provided with an opening within which the bushing 14 and the bearing 13 are mounted. When the bushing and bearing are placed in position and are properly positioned the fastening 65 device 17 is adjusted for clamping them against displacement.

Connected with the shaft 12^a of the cutter is a sprocket wheel 18 which is located in close proximity to the rear face of the cutter 70 11 and is housed within the housing 12. This housing or support 12 is mounted upon the base 18 of the machine and which base also forms a support for the carriage 10, preferably by means of fastening devices 19 75 which pass through slots 20 in a flange 21^a formed on the housing as shown clearly in Figs. 1 and 3. The housing or support is itself supported by means of an eccentrically shaped annular member 21 held in position 80 upon the base of the machine by means of portions 22 extending from the base and projecting into the annular member. These portions 22 are shaped to conform to the contour of the annular member 21 and are 85 spaced from each other a suitable distance so as not to interfere with the sprocket chain 23 which passes between these portions 22, over the sprocket wheel 18 and also over the sprocket wheel 24 secured to the shaft 25 90 which latter constitutes the drive shaft for the cutter and is itself driven in the ordinary and usual manner. Projecting from a suitable portion of the housing 12 and from the inner face thereof are a series of lugs 26 95 which are shaped to conform to the contour of the periphery of the eccentric annular member 21 and engage and rest upon the periphery thereof as shown clearly in Fig. 5 in such a manner that the eccentric member 100 21 will be disposed between the projections 22 and the projecting lugs 26. It will thus be manifest that by rotating the annular member 21 the housing or support 12 will be adjusted upwardly and downwardly and inasmuch as the sprocket wheel 24 remains 105 fixed with respect to the base, and the sprocket wheel 18 is adjusted when the housing or support 12 is adjusted the sprocket chain 23 will be tightened to take up any 110

slack or lost motion. Obviously the fastening devices 19 must first be loosened to permit such adjustment, and after the adjustment they are again tightened.

5 The eccentric annular member 21 is rotated upon the projections 22 in any suitable manner but a simple and efficient means comprises a series of openings 27 arranged therein into which any tool or instrument 10 may be inserted from the outside of the casing and in order to permit such insertion a slot or opening 28 is provided in a portion of the casing adjacent the member 21.

During the constant use and sharpening 15 of the cutter 11, the diameter thereof is reduced and as the machines of this type at present are constructed, the knife when it becomes worn too much will not be as effective as it was before it was worn off before 20 cause the cutting edge will not always maintain the same relative position with respect to the movement of the meat supporting carriage. The present invention and construction as above described obviates this 25 difficulty because when the cutter becomes worn or the diameter thereof decreases, it can be bodily adjusted by simply loosening the fastening devices 19 and then rotating the support 12 upon its support, that is, the 30 supports 22 as indicated in dotted lines in Fig. 1. This will bodily adjust the knife so that it will always be in the proper relative cutting position with respect to the table, without loosening the cutter operating 35 mechanism, after which the fastening device may again be tightened. In Fig. 4 there is shown another means by which this adjustment of the cutter 11 may be accomplished and comprises, as before stated, the 40 bushing 14 within which the bearing 13 is eccentrically mounted. With this form of the invention in order to accomplish the adjustment all that is necessary is to loosen the fastening device 17 and rotate the bushing 14 in its bearing in the end of the support 12 to properly position the knife, after 45 which the fastening device may again be tightened. In Fig. 6 is shown still another means of accomplishing this same adjustment and dispenses with the bushing 14. In 50 this form of the invention the shaft 12^a is eccentrically mounted in the bearing 13 and the adjustment of the knife is accomplished by simply rotating the bearing 13 55 in its support.

While there has been shown and described the preferred forms and construction of the invention, it is to be understood that many changes may be made in the details of construction, combination and arrangement of the several parts without departing from the spirit of the invention.

What is claimed as new is:

1. A slicing machine embodying a cutter, 60 an adjustably mounted support therefor,

driving mechanism for the cutter, a bearing for the cutter, said bearing connected with the support for adjustment with respect thereto to adjust said driving mechanism, and means whereby the support may be adjusted to adjust the cutter without affecting the said driving mechanism. 70

2. A slicing machine embodying a cutter, an adjustably mounted support therefor, driving mechanism for the cutter, eccentric means for adjusting the cutter with relation to the support for adjusting the said driving mechanism, and means whereby the support may be adjusted to adjust the cutter without affecting the said driving mechanism. 75

3. A slicing machine, embodying a relatively movable meat support and cutter, driving mechanism for the cutter, said cutter and support having a fixed relation to each other with respect to the said relative movement, and means operating to maintain such relation when the cutter becomes worn without affecting the driving mechanism. 80

4. A slicing machine embodying a relatively movable meat support and rotatable cutter, means for rotating the cutter, and means for maintaining said cutter and support in a fixed relation to each other with respect to such relative movement, the said means also operating to maintain such fixed relation when the diameter of the cutter becomes reduced and without affecting the cutter rotating means. 85

5. A slicing machine embodying a relatively movable meat support and cutter, an adjustably mounted support for the cutter, operating means for the cutter, said cutter and meat support having a fixed relation to each other with respect to such relative movement, and means whereby the cutter support may be adjusted to maintain such fixed relation of the cutter and meat support when the size of the cutter becomes reduced and without affecting the cutter operating means. 90

6. A slicing machine embodying a relatively movable meat support and cutter, an adjustably mounted support for the cutter, driving mechanism for the cutter, said cutter and meat support having a fixed relation to each other with respect to such relative movement, and means whereby the cutter support may be adjusted to bodily move the cutter in the same cutting plane to maintain such fixed relation of the cutter and meat support when the size of the cutter becomes reduced without affecting the cutter driving mechanism. 100

7. A slicing machine embodying a relatively movable meat support and cutter, said cutter and support having a fixed relation to each other with respect to the said relative movement, and eccentric means for 110

maintaining such relation when the cutter becomes reduced in size.

8. A slicing machine embodying a relatively movable meat support and rotary cutter, said cutter and support having a fixed relation to each other with respect to the said relative movement, and eccentric means for bodily adjusting the cutter and in the same cutting plane to maintain such relation when the diameter of the cutter becomes reduced.

9. A slicing machine embodying a cutter, an adjustably mounted support therefor, operating mechanism for the cutter, eccentric means for adjusting the support to adjust the said operating mechanism and means for adjusting the support without affecting the operating mechanism.

10. A slicing machine embodying a cutter, an adjustably mounted support therefor, driving mechanism for the cutter, means whereby the adjustment of the support will adjust the said driving mechanism and means whereby the support may be adjusted to adjust the cutter without affecting the said driving mechanism.

11. A slicing machine embodying a cutter, an adjustably mounted support therefor, driving mechanism for the cutter, means whereby one adjustment may be given to the support to adjust the driving mechanism and means whereby another and different adjustment may be given to the support to vary the position of the cutter, without affecting the said driving mechanism.

12. A slicing machine embodying a cutter, a support therefor, driving mechanism for the cutter and means adjustably holding the support in position, said support being adapted for one adjustment to take up the slack in the cutter driving mechanism, and being also adapted for another and different adjustment to adjust the cutter without affecting the cutter driving mechanism.

13. A slicing machine embodying a cutter, a support therefor, driving mechanism for the cutter, and means adjustably holding the support in position, said means embodying an eccentric element, said support being capable of one adjustment to tighten the cutter driving mechanism and being also capable of another and different adjustment to shift the cutter without affecting the said driving mechanism.

14. A slicing machine embodying a cutter, a support therefor, driving mechanism for the cutter, and means adjustably supporting the support, said means embodying an eccentric element, said element operating to adjust the support in one direction to adjust the driving mechanism, said support being also capable of adjustment in one direction to adjust the cutter without affecting the driving mechanism.

15. A slicing machine embodying a cutter,

a support therefor, driving mechanism for the cutter, means adjustably supporting the support, said means embodying an eccentric element, said element operating to adjust the support in one direction to adjust the driving mechanism, said support being also capable of adjustment in one direction to adjust the cutter without affecting the driving mechanism, and means operating to secure the support in each of its positions.

16. A slicing machine embodying a cutter, a support therefor, driving mechanism for the cutter, means adjustably supporting the said support, said means embodying an eccentric element having connection with the support whereby the adjustment of the said element will adjust the support, and means supporting the eccentric element for adjustment.

17. A slicing machine embodying a cutter, a support therefor, driving mechanism for the cutter, means adjustably supporting the support, said means embodying an eccentric element having connection with the support for adjusting the latter to tighten the said driving mechanism and means supporting the eccentric element and with respect to which last recited means the eccentric element is adjustable.

18. A slicing machine embodying a cutter, a support therefor, driving mechanism for the cutter, means adjustably supporting the support, said means embodying an eccentric element having connection with the support for adjusting the latter to tighten the said driving mechanism, means supporting the eccentric element and with respect to which last recited means the eccentric element is adjustable, and means for fastening the cutter support against adjustment.

19. A slicing machine embodying a cutter, a support therefor, driving mechanism for the cutter, means adjustably supporting the said support and embodying a rotatable eccentric element having connection with the support to adjust the latter, and means engaging and supporting the eccentric element.

20. A slicing machine embodying a cutter, a support therefor, driving mechanism for the cutter, a rotatable eccentric element having connection with the support for adjusting the latter to tighten the driving mechanism, a support for the eccentric element, and means adjustably securing said eccentric element and supports in operative relation.

21. A slicing machine embodying a cutter, a support therefor, driving mechanism for the cutter, and means securing the support in position for adjustment, said support being bodily adjustable in one direction to tighten the said driving mechanism, and being also pivotally adjustable in another

and different direction to shift the position of the cutter without tightening the said driving mechanism.

22. A slicing machine embodying a cutter, a support therefor, driving mechanism for the cutter embodying spaced elements and a flexible connection therebetween, means embodying an eccentric element for effecting a relative adjustment for the first 10 said elements for tightening the said flexible connection, and means for adjusting the support without affecting the said flexible connection.

23. A slicing machine embodying a relatively movable article support and cutter, the said cutter and support having a fixed relation to each other with respect to such

relative movement, said cutter being capable of bodily adjustment, cutter driving mechanism, and an eccentric element, said cutter 20 being responsive in its bodily adjustment to the movement of the eccentric for adjusting the cutter in the same cutting plane to maintain such fixed relation of the cutter and article support.

25 In testimony whereof I have signed my name to this specification, in the presence of two subscribing witnesses, on this 27th day of March A. D. 1913.

HENDRIK STUKART.
